Primary Examiner — Angela J Lee*Assistant Examiner* — Audris Park(74) *Attorney, Agent, or Firm* — Jose Cherson Weissbrot(57) **CLAIM**

The ornamental design for a rectangular illusion mirror light, as shown and described.

DESCRIPTION

FIG. 1 is a first perspective view of a rectangular illusion mirror light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the rectangular illusion mirror light in which the design is embodied that form no part of the claimed design.
